UNITED STATES PATENT OFFICE

GEORGE GODDU, OF WINCHESTER, MASSACHUSETTS, ASSIGNEE TO UNITED SHOE MACHINERY CORPORATION, OF PATERSON, NEW JERSEY, A CORPORATION OF NEW JERSEY

MANUFACTURE OF SHOES

Application filed June 19, 1924, Serial No. 721,007. Renewed April 23, 1929.

This invention relates to the manufacture of shoes of that type in which there is an insole and an outsole with the outsole secured against the outer face of a portion of the upper that overlies the outer or bottom face of the insole. The invention is herein illustrated as applied to the manufacture of shoes in which the outsole is secured in that relation to the upper by means of stitches 10 penetrating, at least at the time of their insertion, to the inside of the shoe and herein-after frequently referred to as through-and-through stitches.

The present application is, moreover, a continuation, as to common subject-matter, of an earlier application Serial No. 653,291, filed on July 23, 1923.

In the manufacture of shoes of the above-mentioned type it has been heretofore a common practice to fasten the upper to the insole in the lasting operation, along the sides as well as at the toe and heel ends, by tacks that are clinched on the inner face of the insole, and thereafter to apply the outsole over the tacks. Shoes of this kind are in demand among a large class of the trade, since they are less expensive to make and are frequently lighter in appearance than welt shoes, and since they are more durable and more readily 30 repaired than turn shoes. Among the reasons for the comparatively inexpensive character of such shoes are the fact that fewer manufacturing operations are involved than in making welt shoes, the fact that it is not 35 necessary for the shoes to stand after lasting to permit the uppers to set before the manufacturing operations are continued, and the fact that adequate durability does not require the use of a very high grade of insole.

Notwithstanding, however, the manifest advantages which result in a substantial demand for shoes of this kind, they are not used as extensively as they would be if it were not for the presence of the side lasting tacks in 45 the insole. The clinched lasting tacks along the sides of the insole render the shoe considerably less flexible than it otherwise would be and therefore less comfortable to the wearer. A still more serious objection to the presence of these tacks is that their clinched ends

on the inner face of the insole frequently cause discomfort and may cause injury to the wearer of the shoe. This may be due to improper clinching or, more commonly, to the fact that in the wear of the shoe and the constant bending of the insole the tacks have a tendency to become loose and to work up into the interior of the shoe. The rusting of the tacks also frequently causes discolorations on the interior of the shoe. All such objectionable conditions are the more likely to result if the shoes are provided with comparatively light insoles. To overcome these objections and to satisfy an increasing demand for a light, flexible shoe, it has been proposed to 55 fasten the upper along the sides of the shoe in the lasting operation by the use of temporary lasting tacks which are only partially driven and are not clinched, and after the upper has substantially set in lasted shape to 60 insert a comparatively few upper retaining staples through a channel lip formed for the purpose in the bottom of the insole and then to remove the lasting tacks. This procedure, however, adds to the cost of the shoes, not 65 only because it involves additional operations in driving the staples and in removing the tacks, but also because it is necessary for the shoes to stand on their racks after lasting for a number of hours, and it may be for a day 70 or more, to permit the uppers to set, so that the staples thus utilized will be adequate to retain the uppers until the outsoles are applied and secured. This introduces into the manufacture of shoes of the above-mentioned 75 type a substantial element of the extra expense involved in welt shoe manufacture, by reason not only of the additional manufacturing operations, but also of the need of maintaining a large supply of lasts and of racks 80 and of providing ample floor space for storing the shoes between the lasting and the stapling operations. The presence of the lasting tacks, moreover, makes it difficult to 85 insert the staples at regular intervals or in 90 locations such as to insure that they will retain the upper in a satisfactory manner if the staples are inserted before the lasting tacks are removed. Such staple fastenings, therefore, may vary greatly in their effectiveness, 95 100

and the quality of the work after subsequent manufacturing operations depends largely upon the care used in driving the staples. On the other hand, if some of the tacks are removed before the corresponding staples are inserted, there is always danger that the upper will be somewhat displaced from properly lasted position.

It is an object of the present invention to provide an improvement in methods of making shoes of the type in which the outsole is secured directly against the outer face of that portion of the upper that overlies the insole, whereby shoes of this type may be made that are free from the objectionable side lasting tacks without the necessity for the additional manufacturing operations or other elements of additional expense above mentioned, and without danger of objectionable displacement of the upper after lasting. For the accomplishment of this and other objects, the invention provides a method of making shoes of the above-mentioned type, including the characteristic step of securing the outsole against the outer face of the portion of the upper overlying the insole, by which, in preparation for the attachment of the outsole, the upper is fastened to the insole as a part of the lasting operation by the use of permanent fastenings so applied and of such a character as to be unobjectionable in the finished shoe and yet adequate to hold the upper securely in lasted position in the interval between the lasting and the outsole-securing operations. The fastenings are applied in such manner as not to penetrate the inner face of the insole, but are nevertheless securely anchored to the insole. In one mode of procedure, as herein illustrated, the fastenings are driven through a channel lip provided for the purpose and comprising a portion only of the thickness of the insole, and for better insurance of holding the upper securely, the fastenings are shown as driven substantially at the base of the channel lip and are anchored to the insole by clinching them on the inner side of the lip. If the outsole is to be secured by through-and-through stitches, this lip will be located far enough from the edge of the insole to permit the outsole stitches to pass through the insole between the lip and said edge. For the purpose in view, the invention as herein exemplified further provides, as a part of the novel method, for operating upon the upper successively in different locations along the sides of the shoe to position the upper in lasted relation to the insole, as by pulling it and working it over the margin of the insole and against the lip, and while each of the portions of the upper thus operated upon is still under pulling tension or is otherwise held in lasted position or under lasting strain, for inserting a fastening in the manner contemplated to secure it in lasted position. As herein illustrated each fasten-

ing is inserted in the line of the lasting strain, as distinguished from a location at one side of the line of strain. While in some aspects the invention is not limited in respect to the character of the fastenings, important objects of the invention are served by the use of staples to fasten the upper to the insole. Experience has shown that the upper is held with ample security by the use of lasting staples of such fine wire that they cause no appreciable unevenness in the bottom of the shoe, permitting the channel lip, where a lip of this kind is utilized, to be turned down substantially flat after the lasting of the shoe.

While a lip formed as an integral part of the insole by a channeling operation is advantageous in that it provides insurance that the upper will be held securely if the insole is of good quality, it is sometimes considered advantageous to attach a piece of material such as canvas tape to the insole to serve as the lip. This permits the use of insoles that are too thin or of too inferior material to be successfully channeled for the purposes in view, without detracting from satisfactory results in respect to the holding of the upper securely in lasted position.

A shoe of the type referred to made by the method herein illustrated is of superior quality by reason of the fact that the upper is secured in its original lasted condition over the outer face of the insole by permanent metallic fastenings which do not penetrate to the inner face of the insole and are each inserted through a portion of the upper subjected to strain in the lasting of the shoe, so that the upper is held securely in properly lasted position without the presence of the usual clinched side lasting tacks, and a shoe of this character constitutes an important feature of the invention.

The invention will now be more particularly explained by reference to the accompanying drawings and thereafter set forth in the claims.

In the drawings, Fig. 1 illustrates the channeling of an insole for purposes of the present invention.

Figs. 2 3 and 4 illustrate successive operations in the side lasting of the shoe in accordance with the present invention, by the aid of mechanism described and claimed in my prior application hereinbefore mentioned;

Fig. 5 is a perspective view of a portion of the side of the shoe after lasting;

Fig. 6 is a view of a portion of the shoe after the fastening of an outsole by through-and-through stitching, partly in cross-section and partly in perspective, showing the lasting fastenings and also the through-and-through stitches securing the outsole to the insole;

Fig. 7 is a view similar to Fig. 4 illustrating the use of a canvas tape to serve as a lip on an unchanneled insole; and

Fig. 8 shows a portion of an insole provided with a tape for use as illustrated in Fig. 7.

In the illustrated practice of the method of this invention in the manufacture of through-and-through sewed shoes where the insole is of such quality that it may be provided with a channel lip adequate to hold the upper in lasted position, the insole 2 is channeled, as illustrated in Fig. 1, by the use of well-known machinery including a channel knife 4 which makes a cut directed outwardly toward the edge of the insole to provide a channel lip 6 positioned at such distance from the edge of the insole that the through-and-through stitches for securing the outsole to the insole will be located between the lip and the outer edge of the insole. The channel lip will extend along both sides of the insole from the heel seat forwardly to the toe, and may or may not extend also around the toe. If it is desired, as herein illustrated, to fasten the toe end portion of the upper to the insole by the use of lasting tacks as heretofore, the channel lip will preferably extend only to a point at each side of the toe where the toe lasting begins.

The lipped insole and the upper materials are assembled on the last, and on the usual lines of work the upper is then pulled over at the toe and fastened by the pulling-over tacks. Thereafter the sides of the shoe are lasted by subjecting different portions of the upper materials along the sides successively to lasting strain and positioning them in lasted relation to the lipped insole and securing each of the portions thus operated upon to the lip of the insole by inserting a fine wire staple 8 through the upper and the lip and clinching it substantially at the base of the lip to anchor it. In practising the invention by the aid of the machine shown in my said prior application, the upper is pulled by a gripper 10, first in the direction of the dotted lines of Fig. 2 and then inwardly over the insole as illustrated by the full lines; and thereafter the upper, while held yieldingly by the gripper, is pressed down upon the bottom face of the insole outside of the channel lip and against the lip by the action of a staple guiding member 12, as illustrated in Fig. 3. While the upper is still held under lasting strain, as herein illustrated by the gripper and by the pressure of the member 12, a staple is driven in the line of the lasting strain by the staple driver 14, and the legs of the staple are clinched upon an anvil member 16 which engages the insole in its channel and acts also as a channel guide and shoe positioning member to assist in holding the shoe against the pull of the gripper. It will be understood that after these operations have been performed in one location, the shoe is moved along the channel guide 16 to a different location and the same lasting operations are repeated. In this manner the sides of the shoe are lasted progres-

sively, the upper being fastened securely and permanently in lasted position by the staples without opportunity for it to relax between the upper pulling and the fastening operations. It will be noted that the staples are driven in directions inclined to the plane of the insole and substantially perpendicular to the channel lip as the latter is positioned by the channel guide in inclined relation to the outer face of the insole so that the legs of the staples are clinched close to the base of the lip.

After the sides of the shoe have thus been lasted, the toe and heel ends are lasted in the usual manner, the margin of the upper and the channel lip are pressed down along the sides of the shoe, so that the portion of the margin of the upper that is against the lip is substantially parallel to the outer face of the insole, and the outsole 18 is applied and subjected as usual to sole laying pressure. It may be desired also to insert a filler 20 between the insole and the outsole. It will be evident that as the margin of the upper materials and the channel lip are pressed down, before and during the laying of the outsole, the tendency is to tip the staples to positions more nearly perpendicular to the plane of the insole, thereby exerting a further tightening effect upon the upper materials. The ends of the legs of the fine wire staples, clinched as hereinbefore explained, embed themselves in the substance of the insole in such manner that they interfere in no appreciable degree with the flattening down of the channel lip, nor are they perceptible in any way after the completion of the shoe.

After the sole laying operation, in accordance with the procedure herein illustrated, the last is removed and the outsole is secured against the outer face of that portion of the upper that overlies the insole by through-and-through stitches 22. These stitches may terminate in a channel formed in the outer face of the outsole, as usual, and as herein illustrated extend entirely through the insole.

Instead of channeling the insole, it may be preferable on some lines of work, for example where the insole is very thin or of poor quality, to secure a piece of extraneous material to it to serve as the upper-attaching lip. Fig. 7 illustrates the practice of the method by the use of a lip of this character, such lip comprising, for example, a strip of canvas tape 24 which is secured to the insole by through-and-through stitches. In this case the tape is positioned against the member 16 for guiding and positioning the shoe and the staples are driven through the tape and are clinched thereon closely adjacent to the surface of the insole. After the lasting the tape is turned down flat upon the bottom surface of the insole with the margin of the upper materials, and the subsequent operations in

the manufacture of the shoe are carried out in the same manner as hereinbefore explained. It will be evident that where such tape or other material is stitched to the insole to provide the lip it serves further to reinforce the insole, thereby adding to the strength and durability of the shoe.

It will be appreciated from the foregoing description that the present invention provides a method of making, in an economical manner, a so-called "tackless" shoe. The fine wire staples, extending only part way through the thickness of the insole, do not add to the bottom of the shoe that stiffness which has been an objection heretofore to the use of the side lasting tacks, nor do these staples render the inner surface of the insole uneven or otherwise detract from the comfortable wearing qualities and the good appearance of the shoe. The fact, moreover, that in the practice of the method of this invention the upper is fastened permanently to the insole in the lasting of the shoe is an important advantage, not only by reason of the substantial economies in labor, time and materials as compared with methods involving the use of temporary lasting tacks, but for the further reason that there is no danger of displacement of any portion of the upper after lasting as there is where the lasting fastenings are removed and others substituted.

Having explained the nature of the invention and set forth fully how it may be practised, what I claim as new and desire to secure by Letters Patent of the United States is:

1. That improvement in methods of making shoes having an insole and an outsole, which consists in operating upon the upper successively in different locations along the edge of the shoe bottom to subject it to lasting strain and to position it in lasted relation to the insole, securing the upper to the insole in each of said locations while holding it under lasting strain and before the next succeeding portion of the upper is subjected to lasting strain by driving a metallic fastening through a portion of the upper which is under strain and anchoring the fastening without penetrating the inner face of the insole, and thereafter applying the outsole over the insole and securing it to the insole by a row of fastenings extending at the time of their insertion to the inside of the shoe.

2. That improvement in methods of making shoes having an insole and an outsole, which consists in gripping and pulling the upper successively in different locations along the edge of the shoe bottom to shape it over the last and laying it over the insole in each of said locations by pressure applied thereto substantially in the line of the pulling strain, fastening the upper to the insole in each of said locations, before pulling it in the next succeeding location, by driving a

staple through the portion of the upper to which the pressure is applied and anchoring the staple without penetrating the inner face of the insole, and thereafter applying the outsole over the insole and securing it to the insole by a row of stitches extending at the time of their insertion to the inside of the shoe.

3. That improvement in methods of making shoes having an insole and an outsole, which consists in providing the insole with a lip on its bottom face, subjecting the upper successively in different locations along the edge of the shoe bottom to lasting strain and pressing it while under the lasting strain against the lip of the insole, supporting the lip in each of said locations in turn by a clinching tool presented to the lip in the different locations successively, driving a metallic fastening through the upper and the lip in each of said locations and clinching the fastening on said clinching tool while the upper is held pressed against the lip, and thereafter applying the outsole over the insole and securing it to the insole by a row of stitches extending at the time of their insertion to the inside of the shoe.

4. That improvement in methods of making shoes having an insole and an outsole, which consists in providing the insole with a lip on its bottom face, gripping and pulling the upper successively in different locations along the edge of the shoe bottom to tension it over the last and laying it while under tension over the margin of the insole and against the lip, supporting the lip in each of said locations in turn by a clinching tool presented to the lip in the different locations successively and having its engagement with the lip limited to local engagement in the same plane perpendicular to the bottom of the last as the line of the pulling strain applied to the upper, driving a metallic fastening through the upper and the lip and clinching it on the clinching tool in each of said locations prior to the pulling of the upper in the next succeeding location, and thereafter applying the outsole over the insole and securing it to the insole by a row of fastenings extending at the time of their insertion to the inside of the shoe.

5. That improvement in methods of making shoes having an insole and an outsole, which consists in providing the insole with a lip on its bottom face, subjecting different portions of the upper to lasting strain to shape the upper over the last and to position it in lasted relation to the insole, fastening the different portions of the upper to the insole while they are under the lasting strain by driving staples through the upper and the lip of the insole each in the line of the lasting strain and clinching the staples, and thereafter applying the outsole over the in-

sole and securing it to the insole by through-and-through stitches.

6. That improvement in methods of making shoes having an insole and an outsole, which consists in providing the insole with a lip on its bottom face, operating upon the upper successively in different locations along the sides of the shoe to tension it over the last and to position it in lasted relation to the insole, at the end of each of the operations upon the upper and before tensioning the upper in the next succeeding location, securing the portion operated upon to the insole by driving a staple through that part of the upper to which the tension has been applied and through the insole lip and clinching the staple, and thereafter applying the outsole over the insole and securing it to the insole by through-and-through stitches.

7. That improvement in methods of making shoes having an insole and an outsole, which consists in providing the insole with a lip on its bottom face, pulling a portion of the upper over the last and securing it to the lip of the insole by driving a staple through the upper in the line of the pulling strain and through the lip of the insole and clinching the staple, repeating these upper pulling and stapling operations in different locations along the sides of the shoe, and thereafter applying the outsole over the insole and securing it to the insole by through-and-through stitches.

8. That improvement in methods of making shoes having an insole and an outsole, which consists in providing the insole with a lip on its bottom face, subjecting different portions of the upper successively to lasting strain to shape the upper over the last and fastening each of said portions while under the lasting strain to the lip of the insole with the lip positioned at a substantial angle to the plane of the insole, turning the lip downwardly in a direction away from the edge of the insole and thereby further tightening the upper, and thereafter securing the outsole to the insole by through-and-through stitches.

9. That improvement in methods of making shoes having an insole and an outsole, which consists in providing the insole on its bottom face with a lip extending along its side margin widthwise of the insole and having its inner edge upturned from said face, operating upon the upper successively in different locations along the sides of the shoe to position different portions of the upper in lasted relation to the insole, at the end of each of the operations upon the upper and before operating thereon in the next succeeding location, securing the portion operated upon to the insole by inserting a staple through the upper and the upturned lip in a direction substantially perpendicular to said lip and clinching the staple, turning back

the lip to lie substantially flat upon the insole and thereby further tightening the upper, and thereafter securing the outsole to the insole by through-and-through stitches.

10. That improvement in methods of making shoes having an insole and an outsole, which consists in providing the insole with a lip on its bottom face extending at an angle to said face, operating upon the upper successively in different locations along the sides of the shoe to position different portions of the upper in lasted relation to the insole, at the end of each of the operations upon the upper and while holding the upper in lasted position prior to operating thereon in the next succeeding location, securing the portion operated upon to the insole by inserting a staple through the upper and the lip in a direction inclined to the plane of the insole to position the legs of the staple close to the base of the lip, clinching the legs of the staple, turning the lip downwardly in a direction away from the edge of the insole to lie substantially flat upon the insole, and thereafter securing the outsole to the insole by through-and-through stitches.

11. That improvement in methods of making shoes having an insole and an outsole, which consists in securing on the bottom face of the insole a strip of material to serve as an upper-attaching lip, lasting the shoe by positioning different portions of the upper successively in lasted relation to said insole and lip and securing each of said portions while it is under lasting strain or pressure to the lip by driving a staple through the upper and the lip before the next succeeding portion of the upper is thus positioned, and thereafter applying the outsole over the insole and securing it to the insole by through-and-through stitches.

12. That improvement in methods of making shoes which consists in tensioning an upper over a last successively in different locations along the sides of the last and also laying the margin of the upper successively in different locations over the outer face of an insole on the last, securing each of the overlaid portions of the margin of the upper to the insole, before laying the upper over the insole in the next succeeding location, by a metallic fastening so applied as to anchor it without penetrating the inner face of the insole, and thereafter applying an outsole over the insole and securing it against the outer face of that portion of the upper that overlies the insole.

13. That improvement in methods of making shoes which consists in gripping and pulling an upper over a last successively in different locations along the sides of the last and laying the margin of each of the tensioned portions of the upper in lasted position over the outer face of an insole on the last, secur-

ing each portion of the margin of the upper to the insole, before pulling the upper in the next succeeding location, by driving a staple and anchoring it in such relation to the insole as not to penetrate the inner face of the insole, and thereafter applying an outsole over the insole and securing it against the outer face of the margin of the upper overlying the insole.

14. That improvement in methods of making shoes which consists in providing an insole with a lip on its outer or bottom face at a distance from its edge and mounting the insole on a last, tensioning an upper over the last successively in different locations along the sides of the last and also laying the margin of the upper successively in different locations over the outer face of the margin of the insole and against the lip, securing each of the overlaid portions of the margin of the upper to the insole, before laying the upper over the insole in the next succeeding location, by driving a metallic fastening through the upper and the lip and clinching the fastening, and thereafter applying an outsole over the insole and securing it against the outer face of that portion of the upper that overlies the margin of the insole.

15. That improvement in methods of making shoes which consists in providing an insole with a lip on its outer or bottom face at a distance from its edge and mounting the insole on a last, gripping and pulling an upper over the last successively in different locations along the sides of the last and laying the margin of each of the tensioned portions of the upper in lasted position over the outer face of the margin of the insole and against the lip, supporting the lip adjacent to each of the overlaid portions of the margin of the upper by a clinching tool presented in engagement with the different portions of the lip successively, securing each of the overlaid portions of the margin of the upper to the insole, before laying the upper over the insole in the next succeeding location, by driving a staple through the upper and the lip and clinching it on said clinching tool, and thereafter applying an outsole over the insole and securing it against the outer face of that portion of the upper that overlies the margin of the insole.

16. That improvement in methods of making shoes which consists in providing an insole with a lip on its outer or bottom face at a distance from its edge and mounting the insole on a last, tensioning an upper over the last successively in different locations along the sides of the last and also laying the margin of the upper successively in different locations over the outer face of the margin of the insole and against the lip with the lip positioned at an angle to said face, securing each of the overlaid portions of the margin of the upper to the insole, before laying the upper

over the insole in the next succeeding location, by driving a metallic fastening through the upper and lip and clinching the fastening, turning the lip downwardly to position that portion of the margin of the upper which is against it in substantially parallel relation to the outer face of the insole, and thereafter applying an outsole over the insole and securing it against the outer face of that portion of the upper that overlies the insole.

17. A shoe provided with an insole and an outsole and having the margin of its upper along its opposite sides secured in its original lasted condition over the outer face of the insole by staples driven through portions of the upper subjected to strain in the lasting of the shoe and so applied as not to penetrate the inner face of the insole although anchored to the insole and having its outsole secured against the outer face of that portion of the upper that overlies the insole.

18. A shoe provided with an insole and an outsole and having the margin of its upper along its opposite sides secured in its original lasted condition over the outer face of the insole by staples driven through portions of the upper subjected to strain in the lasting of the shoe and through a lip on the insole so arranged that the portion of the margin of the upper secured thereto is substantially parallel to the outer face of the insole, and having its outsole secured against the outer face of that portion of the upper that overlies the insole.

19. A shoe having its upper secured in its original lasted condition to the outer face of the insole by permanent metallic fastenings each inserted in the line of the lasting strain on the upper through a lip on the insole and clinched on the inner face of the lip and having its outsole secured to the insole by through-and-through stitches between the edge of the insole and said fastenings.

In testimony whereof I have signed my name to this specification.
